(57) **CLAIM**

The ornamental design for a contact lens cleaner case, as shown and described.

DESCRIPTION

FIG. 1 is a perspective view of the contact lens cleaner case of my design, viewed from the front and top;

FIG. 2 is a top plan view thereof;

FIG. 3 is a bottom plan view thereof, and the broken lines in FIG. 3 are included for the purpose of illustrating a portion of the contact lens cleaner case that forms no part of the claimed design;

FIG. 4 is a left side elevational view thereof;

FIG. 5 is a right side elevational view thereof;

FIG. 6 is a front elevational view thereof;

FIG. 7 is a perspective view thereof, viewed from the rear and top, with one cap removed;

FIG. 8 is a top plan view thereof, with one cap removed; and,

FIG. 9 is a top plan view thereof, with both caps removed.
